FIG. 1 is a perspective view of a decorative object. The object is a cluster of five rounded, textured shapes. The shapes are arranged in a roughly spherical, overlapping configuration. The surface of the shapes has a fine, repeating dot pattern, giving it a textured appearance. The lighting creates highlights and shadows on the rounded surfaces, emphasizing their three-dimensional form.

FIG. 2 is a perspective view of a decorative object. The object is a cluster of five rounded, textured shapes. The shapes are arranged in a roughly spherical, overlapping configuration. The surface of the shapes has a fine, repeating dot pattern, giving it a textured appearance. The lighting creates highlights and shadows on the rounded surfaces, emphasizing their three-dimensional form. The shapes are identical to those in FIG. 1.

FIG. 16

FIG. 17 is a perspective view of a decorative floral arrangement, including a base 100, a central floral cluster 110, and a surrounding arrangement of flowers 120. The arrangement is designed to be displayed on a surface, such as a table or shelf. The base 100 is a simple, light-colored rectangular block. The central floral cluster 110 is composed of several flowers, including roses and hydrangeas, arranged in a tight, spherical cluster. The surrounding arrangement of flowers 120 consists of a variety of smaller flowers, including carnations and lilies, arranged in a more open, circular pattern around the central cluster. The entire arrangement is presented in a black and white photograph.

FIG. 17

FIG. 18 is a perspective view of a decorative floral arrangement, including a base 200, a central floral cluster 210, and a surrounding arrangement of flowers 220. The arrangement is designed to be displayed on a surface, such as a table or shelf. The base 200 is a simple, light-colored rectangular block. The central floral cluster 210 is composed of several flowers, including roses and hydrangeas, arranged in a tight, spherical cluster. The surrounding arrangement of flowers 220 consists of a variety of smaller flowers, including carnations and lilies, arranged in a more open, circular pattern around the central cluster. The entire arrangement is presented in a black and white photograph.
